UNITED STATES PATENT OFFICE.

FRANK W. LEIDECKER, OF OKMULGEE, OKLAHOMA.

CHECK AND RELEASE VALVE FOR WELL SWABS.

1,405,048.

Specification of Letters Patent. Patented Jan. 31, 1922.

Application filed June 5, 1920. Serial No. 286,810.

To all whom it may concern:

Be it known that I, FRANK W. LEIDECKER, a citizen of the United States, residing at Okmulgee, in the county of Okmulgee and State of Oklahoma, have invented a new and useful Check and Release Valve for Well Swabs, of which the following is a specification.

The present invention relates to relief valves to be secured at the lower end of a swab employed in drilling oil wells, the swab being designed for removing the fluid from the well.

The primary object of the invention is to provide a relief valve which will prevent the lifting of a greater quantity of fluid than that which the swab is designed to carry, thereby eliminating any possibility of breaking the swab during the swabbing operation.

A further object of the invention is to provide a valve of this character which may be set to discharge a quantity of the fluid lifted by the swab in the event that the swab is dropped into the well at a point to cause the swab to lift too great a quantity of fluid.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 illustrates a front elevational view of a relief valve constructed in accordance with the present invention.

Figure 2 illustrates a longitudinal sectional view through the relief valve.

Referring to the drawing in detail, the reference character 5 designates the valve casing which is substantially tubular in formation, and is provided with an inwardly extending flange 6, formed substantially intermediate the ends thereof, the flange being of a diameter to provide an opening 7 for the purposes to be hereinafter more fully described.

Formed within the upper extremity of the casing 5 are the threads 8, which cooperate with the usual threads disposed at the end of a swab, for securing the valve casing

thereto, so that the valve casing will move with the swab.

A lateral threaded opening 9, is formed in the casing 5, which opening accommodates the plug 10, that is provided with a plurality of openings indicated at 11, for providing communication between the interior of the casing and the atmosphere, so that fluid may pass into the casing 5, through said openings, the openings being controlled however by means of the circular valve 12 that has connection with the valve stem 13 operating in the opening 14, formed in the plug 10.

This valve 12, is preferably circular in formation and is adapted to seat against the shoulder 15, formed on the inner edge of the plug 10, the inner extremity of the stem 13 supporting the coiled spring 16, which has one end thereof disposed in a cut out portion 17 formed interiorly of the casing 5, the opposite end of said coiled spring engaging one surface of the valve 12, for normally seating the valve 12.

A plug 18 is threaded into the lower portion of the casing 5, and this plug is provided with a central opening to accommodate the valve stem 19, which has the disk valve 20 at the upper extremity thereof, which disk valve is held in engagement with the flange 6, by means of the coiled spring 21 but is adapted to move out of engagement with the flange, when the weight of the fluid within the casing overcomes the tension of the coiled spring 21, thus permitting the fluid within the casing 5 to exhaust through the openings 22 until the tension of the coiled spring 21 is sufficient to seat the valve member 20.

From the foregoing it is obvious that by movement of the plugs 10 or 18, the valve members which are supported thereby, may be adjusted to cause the operation thereof under various weights of fluid.

In the operation of the device it is obvious that when the swab carrying the relief valve, is dropped into a well, the fluid will flow into the casing until the desired amount has entered above the swab. Any excess of fluid acts against the disk valve 20, to unseat the same and permit fluid to exhaust through the openings 22 which are disposed above the discharge.

Having thus described the invention, what is claimed as new is:

1. A check and release valve for well

swabs comprising a casing, means for dividing the casing into an upper compartment and a lower compartment, means for admitting fluid laterally of the upper compartment, and means for permitting fluid to pass from the upper compartment to the lower compartment under a predetermined weight.

2. A check and release valve for well swabs comprising a casing, said casing including an upper compartment and a lower compartment, a valve for controlling the passage of fluid into the upper compartment, a valve for controlling the passage of fluid into the lower compartment, and said casing having openings to permit fluid to pass from the lower compartment.

3. A check and release valve for well swabs, comprising a casing including an upper compartment and a lower compartment, said compartments being in communication, means for controlling the passage of fluid into the upper compartment, an adjustable valve for controlling the passage of fluid from the upper compartment to the lower compartment, and said casing having openings to permit the passage of fluid from the lower compartment.

4. A check and release valve for well swabs comprising a casing including an upper compartment and a lower compartment,

ment, a valve providing a movable bottom for the swab, means for adjusting the valve to permit the same to operate under a predetermined weight, means for controlling the passage of fluid into the upper compartment, and said casing having openings to permit fluid to pass from the lower compartment.

5. A check and release valve for well swabs comprising a casing, said casing having internal threads at its respective ends, a flange for dividing the casing into an upper and lower compartment, said casing having a lateral threaded opening, a plug disposed in the opening and having a plurality of inlet openings, a spring pressed valve for controlling the passage of fluid into the upper compartment, a movable valve forming the bottom of the upper compartment, and said casing having openings to permit the passage of fluid from the lower compartment.

In testimony that I claim the foregoing as my own, I have hereto affixed my signature in the presence of two witnesses.

FRANK W. LEIDECKER.
